ELECTROMAGNETIC DEVICE

Frederic E. Wood, Hinsdale, Ill., assignor to Associated Electric Laboratories, Inc., Chicago, Ill., a Corporation of Delaware

Application November 21, 1931
Serial No. 576,529

7 Claims. (Cl. 200—87)

This invention relates in general to electromagnetic devices, but more particularly to electromagnetic relays such as are used as circuit breakers for high tension circuits, and the principal object of the invention is concerned with the provision of supporting and adjusting means of the circuit breakers in relays of this type.

A particular type of electromagnetic circuit breaker which is coming into more common use, due to the many advantages it possesses, is a type wherein a pair of contacts carrying high tension current are mounted in a sealed glass tube containing a high degree of evacuation. The actuation of these contacts is brought about through the action of a glass rod acting as a lever which makes use of the elastic property of the glass to cause a mechanical actuation of the contacts in the glass tube. Corroding and arcing of the contacts is thereby prevented. Considerable difficulty has been encountered in devising means for mounting or supporting the evacuated glass tube due to its fragile and delicate nature since it must be supported so that the means, either manually or electromagnetically operated for actuating the rod, does not injure the device. Accordingly, it is an object of the invention to design suitable supporting and mounting means for a glass tube containing a circuit breaker of the nature described.

Another object of the invention is to devise suitable adjusting means for positioning the glass tube and rod with respect to its actuating device so that the proper adjustment of the contacts of the circuit breaker is brought about.

Other objects of the invention are concerned with the provision of suitable brackets or mounting plates for supporting one or more glass tubes or containers on various types of relays.

The invention is described in connection with the attached sheet of drawing which shows the preferred embodiment of the invention. Referring to the drawing; Fig. 1 shows a top view of an alternating current operated electromagnetic device having a single glass tube and circuit breaker supported thereon; Fig. 2 shows a side view of the same device, while Fig. 3 shows a perspective view of a bracket arrangement and supporting assembly for the glass circuit breaker; Fig. 4 shows a top view of a direct current operated electromagnetic device employing a pair of glass circuit breakers supported by means of a bracket on the heel piece; Fig. 5 discloses a perspective view of the supporting and mounting arrangement for the circuit breaker shown in Fig. 4; while Fig. 6 shows another per-

spective view of the bracket arrangement of Fig. 4.

Referring to the modification shown in Figs. 1, 2, and 3, this electromagnetic device is of the type which is suitable for operation with alternating current. A device of this nature is disclosed in more detail in a co-pending application of John Erickson, Serial No. 538,058, filed May 18, 1931, which became Patent No. 1,883,773 on Oct. 18, 1932. A circuit breaker of the type shown in the drawing in which the contacts are enclosed in a sealed glass tube containing a high degree of evacuation is disclosed in the August 8, 1931, issue of *Telephony Magazine*, page 42, and need not further be described. The electromagnetic device disclosed in Fig. 4 is an ordinary direct current relay such as is well known in the telephone art.

In Fig. 1 the electromagnetic device shown is such that, due to the nature of its construction as pointed out in the aforementioned pending application, it is adapted to be operated with alternating current. It comprises a coil 1 having a winding wound thereon which is supported on a U-shaped laminated core 2. The armature 3 is suitably supported and pivoted opposite one end and one leg of the core 2 onto the bracket arrangement 4 so that the air gap may be suitably varied. The armature 3 has an arm carrying an insulated bushing 5 for actuating the circuit breaker as will be pointed out. A flat metal heel piece 6 is supported on the laminated core 2 on one side thereof, and forms a support for the bracket 7 which is attached to the heel piece 6 by means of screws 8. A pair of relatively flexible discontinuous metal bands 9 and 10 are supported by screws 12 and 13 onto the lower turned up end of the bracket 7. A flat metal strip 11 clamps the metal bands 9 and 10 by the screws 12 and 13 direct onto the bracket 7. The bands 9 and 10 have openings, through which the screws 12 and 13 pass, which are in the form of slots as shown at 14 so that these bands may be adjusted up or down to slightly vary the longitudinal position of the sealed glass tube 15 which is supported on either end by the metal bands 9 and 10. The bands it will be seen only partially encircle the tube 15, leaving a slight gap where they are supported, so that a certain amount of flexibility is imparted to them. The glass tube 15 contains sealed therein under a high degree of vacuum, a pair of contacts 16 which are actuated by the glass stem 17 projecting from the tube 15 and which is normally tensioned against the bushing 5 of the armature 3 by the tension spring 18 so as to

maintain the stem in a normal position. The tension spring 18 is suitably insulated and supported as by screws 19 onto an extension of the bracket 7.

- 5 With the construction shown and described it is seen that longitudinal movement of the tube 15 will likewise move the stem 17 along the side of the bushing 5 of the armature 3 so that the fulcrum point of the stem 17 somewhere between 10 the bushing 5 and the contacts 16 may be relatively changed to either normally adjust the contacts to a wider gap when they are actuated, or to a narrow one, as desired. Similarly loosening either screws 12 and 13 and moving the metal 15 bands 9 and 10 up or down will move the glass tube 15 at a slight inclination from its horizontal position so that a further variation of the opening of the contacts may be effected after the screws 12 and 13 are tightened.
- 20 As shown in the drawing, the contacts 16 are normally closed and upon actuation of the armature 3 a movement of the end of the stem 17 is effected and this in turn by means of the elastic properties of the glass tube moves the opposite 25 end of the stem 17 against movable contacts 16 to open them. When it is desired to have the contacts in a normally opened instead of closed position, it is merely necessary to rotate the tube 15 one-hundred and eighty degrees about its axis 30 inside of the metal bands 9 and 10, and after this is done it is necessary to loosen the screws 12 and 13 and move the metal bands 9 and 10 either up or down with respect to each other in the slots 14 and also increase the tension of the restoring 35 spring 18 to normally hold the contacts open.

When the armature 3 is then operated the contacts will assume a closed position instead of open.

- In the modification shown in Fig. 4, an ordinary 40 direct current type of telephone relay is disclosed having a form of counting bracket which is adapted to support a pair of glass tubes. This bracket 23 is supported on the flat heel piece 6' of the relay 1' at points 25 on the front and 26 45 on the rear of the bracket by means of screws. The relatively flexible metal bands 19 and 20 are supported on one turned up edge of the bracket 23, while the metal bands 21 and 22 are supported 50 on the opposite turned up edge of the bracket 23. These metal bands are clamped together in pairs by means of the metal strips 28 and 29 and secured to the plate 23 by screws. Each of the metal bands 19, 20, 21, and 22 have a slot, similar to slot 14 shown in Fig. 3, so that they may be 55 shifted up or down to move the glass tubes 15¹ and 15² for the purpose pointed out hereinbefore. An upwardly projecting extension 24 of the bracket 23 supports a pair of spring members 27 and 30 suitably insulated from the support 24 60 so that these spring members project above each of their respective glass tubes 15¹ and 15² to engage the ends of the stems such as 17' and hold the stems against the armature bushings 5'.

- With the form of construction of the bracket 65 shown in Figs. 5 and 6 a pair of glass tubes having circuit breakers therein may be positioned and actuated by a single electromagnetic relay, and if desired one of the circuit breakers may be of the type in which the contacts are normally closed 70 while the other one may be of the type in which the contacts are normally opened. With the adjustment provided due to the slots in the metal bands for holding the glass tubes, together with the longitudinal movement of the tube which 75 is permitted due to the flexibility of the metal

bands, a wide variation of adjustment, and contact actuation by the armature, is obtained. From the above description, together with the drawing it is seen that a novel type of mounting arrangement, for adjustably supporting a circuit breaker contained within an evacuated glass tube, has been designed, and it is seen that any slight modification apparent to those skilled in the art may be incorporated in the particular arrangement disclosed. What is thought to be novel and desired to be protected by Letters Patent is pointed out in the following claims.

What is claimed is:

1. In an electromagnetic device having an armature and a circuit breaker of the type mounted within an evacuated glass container, a bracket mounted on said device, a stem on said glass container for actuating said circuit breaker at one end and having the other end in operative relation to the armature so as to be actuated thereby, an extension on said bracket having means supported thereon for actuating said stem in opposition to the armature to restore said circuit breaker to normal position after said armature has actuated the stem, a pair of flexible bands encircling said glass container at spaced intervals, and adjustable means for mounting said metal bands on said bracket so as to vary the relationship of the stem with respect to the armature and the circuit breaker. 80
2. In an electromagnetic device having an armature and a circuit breaker contained in a sealed glass tube actuated by the armature, a bracket mounted on said device, a pair of flexible metal bands spaced apart and partially encircling said glass tube to support the same, a stem in said glass tube for actuating the circuit breaker and having one end in operative relation to the armature, said metal bands permitting the longitudinal movement of said glass tube 90 so as to move said stem toward the armature and vary the extent of movement of the stem with respect to the armature and the circuit breaker, and adjustable means for supporting said metal bands on said bracket so as to further vary the relationship of the stem with respect to the armature and the circuit breaker. 95
3. In an electromagnetic device having an armature and a circuit breaker comprising a pair of contacts mounted in an evacuated glass tube, 100 a bracket for said tube supported on said device, a pair of flexible metal bands engaging said tube and partially encircling the same for supporting it in a manner so that longitudinal movement may be imparted to the tube, a fulcrumed 105 stem in said vessel having one end in operative engagement with the armature and the opposite end controlling the pair of contacts, the longitudinal movement of said glass tube varying the fulcrum of said stem with respect to the armature and the contacts, and means comprising a slot in each of said metal bands for supporting the same on said bracket and for adjustably 110 varying the position of either one of said bands in a direction at right angles to said longitudinal movement of the glass tube to still further adjust the relationship of the stem with respect to the armature and the contacts. 115
4. In an electromagnetic device having an armature and a pair of contacts, said contacts 120 mounted in a sealed glass tube and actuated by the armature through the medium of a contact carrying flexible portion of said tube, a bracket supported on said device and having an extension thereon projecting above said glass tube, 125
5. In an electromagnetic device having an armature and a pair of contacts, said contacts 130 mounted in a sealed glass tube and actuated by the armature through the medium of a contact carrying flexible portion of said tube, a bracket supported on said device and having an extension thereon projecting above said glass tube, 135
6. In an electromagnetic device having an armature and a pair of contacts, said contacts 140 mounted in a sealed glass tube and actuated by the armature through the medium of a contact carrying flexible portion of said tube, a bracket supported on said device and having an extension thereon projecting above said glass tube, 145
7. In an electromagnetic device having an armature and a pair of contacts, said contacts 150 mounted in a sealed glass tube and actuated by the armature through the medium of a contact carrying flexible portion of said tube, a bracket supported on said device and having an extension thereon projecting above said glass tube, 150

25 a pair of flexible metal bands partially encircling said glass tube and holding the tube in fixed relation to said device, said glass tube arranged in one position to normally maintain said pair of contacts closed and in another position normally maintain the contacts open, means on said bracket extension for restoring the contacts to either normal position after actuation by the armature, and means for adjustably supporting said metal bands on said bracket to accommodate the different positions of said glass tube.

5 5. In a relay structure, a magnet, a heel piece secured to the core at one end of said magnet and extending alongside the magnet throughout its length; means for supporting a circuit switching device, comprising a hermetically sealed vessel of vitreous elastic material within which is enclosed a pair of switching contacts operable by an elongated tubular extension formed of the vitreous material, on said heel piece parallel thereto and to said magnet; and an armature mounted on the free end of said heel piece and having one end thereof in operative relation to

the core of said magnet and the other end thereof in operative relation with the tubular extension of the circuit switching device.

10 6. In combination with a circuit switching device comprising a sealed vessel of vitreous elastic material within which is enclosed a pair of switching contacts operable by an elongated tubular extension formed of a continuation of the material from which the vessel proper is made, a magnet having a heel-piece, a bracket arrangement holding the vessel in fixed relation to said heel-piece; and an armature, arranged to be operated by said magnet, fixed to said heel-piece in operative relation to the tubular member of said switching device.

15 7. In a combination of the character specified in the preceding claim, characterized in that, the bracket arrangement is arranged to support a plurality of such switching devices, while the armature is arranged with as many arms as there are tubular members.
